UNITED STATES PATENT OFFICE.

HENRY H. LOGAN, OF CHICAGO, ILLINOIS.

AUTOMATIC BRAKE OPERATOR FOR INCLINE HOISTS.

Application filed September 10, 1926. Serial No. 134,743.

My invention relates to improvements in automatic brake operator for incline hoist, and it consists in the combinations, constructions, and arrangements herein described and 5 claimed.

An object of my invention is to provide an automatic brake operator for inclined hoist which is designed to work in conjunction with a standard safety device for mine 10 hoists, and to eliminate some of the dangers and difficulties encountered in operating a mine hoist to raise and lower a train of cars on slopes or inclines.

A further object of my invention is to 15 provide a device of the type described which may be applied to any controller for hoisting engines, but which is specially adapted to be applied to the hoisting engine controls of Lilly et al., Serial No. 627,504, filed March 20 24, 1923.

A further object of my invention is to provide a device of the type described in which the parts are reversible to be applied to either a clockwise or a counter-clockwise 25 rotating controller.

Other objects and advantages will appear in the following specification, and the novel features of the invention will be particularly pointed out in the appended claims.

30 My invention is illustrated in the accompanying drawings, forming part of this application, in which

Figure 1 is a front elevation of the device as applied to a hoist control,

35 Figure 2 is a side elevation of the device as applied to a hoist control,

Figure 3 is a wiring diagram,

Figure 4 is a side elevation of a portion of 40 a hoist control as operatively connected to my device, and

Figure 5 is an end elevation of a portion of the structure shown in Figure 4.

In carrying out my invention, I provide 45 a frame 1 having a relatively large flange portion 2. The flange portion 2 is provided with openings 3 for receiving machine screws 4 by means of which the frame 1 is secured to the frame H of a hoist control. The frame 1 is also secured to the frame H at 50 5 by means of machine screws 6. The flange portion 2 is further provided with an opening 7 for receiving the shaft 8 of the hoist control.

A toothed disc 9 is removably secured to a 55 hub 10 which is keyed upon the shaft 8. A

bracket 11 is removably secured to the frame 1 at the upper end thereof by means of a machine screw 12, and at the lower end thereof by means of a bolt 13. A latch arm 14 is rotatably mounted upon the bolt 13 adjacent the frame 1, and is provided with a latch 15 at the lower end thereof. A V-shaped groove 16 is formed in the latch 15 in direct alignment with the center of the bolt 13 and the center of the shaft 8 when the arm 14 is in normal position. The latch arm 14 is held in normal position by means of a spring 17. The latch arm 14 is provided with an upwardly extending portion 18 upon which a forked weight arm 19 is pivotally mounted 70 upon a pin 19'. The forked arm 19 is provided with a pin 20 having a flattened surface 21. A pawl 22 is pivotally mounted upon the pin 19' between the forks of the weight arm 19, and is provided with a laterally extending pin 23 which is adapted to engage with a lug 24 upon the weight arm 19 for holding the pawl 22 in normal position. The end 25 of the pawl is positioned so as to engage with teeth 26 of the disc 9. A 75 cam 27 is pivotally mounted upon the bolt 13 and is positioned between the forks of the weight arm 19. The cam 27 is provided with a cutaway portion 28 for receiving the pin 20 when in normal position. A cam-actuating arm 29 is pivotally mounted upon the bolt 13 and is provided with tongues 30 which are adapted to be received within grooves 31 of the cam 27. The free end of the arm 29 is forked to pivotally receive one 80 end of a connecting rod 32. The free end of the connecting rod 32 is pivotally secured to a core 33 of a solenoid 34. Flanges 35 and 36 are provided upon each side of the bracket 11 to which the solenoid 34 may be 85 secured. In the present instance, the solenoid is secured to the flange 35.

The solenoid 34 is in electrical connection with the circuit of the hoist control. In Figure 3, I have shown a wiring diagram 100 illustrating the solenoid 34 in connection with the electrical circuit of a hoist control. Conductors 37 and 38 represent a source of current with which a transformer 39 is in direct connection. The protective contactor is indicated at 40, the zero reset switch is indicated at 41, and the overspeed switch is indicated at 42.

A level 43 is in direct connection with the 105 brake mechanism for the hoist drum. The 110

hoist drum and brake mechanism are well known in the art and have acquired a distinct status therein.

From the foregoing description of the various parts of the device the operation thereof may be readily understood. Without a device of this character, in case the power fails while hoisting a trip, or if the safety device cuts the power off, due to retardation not being conducted properly, especially when the cars are traveling at considerable speed on a flat part of the slope, it is impossible to prevent them from running ahead of the rope until their momentum is spent, and then reversing and going down the slope again, taking up the slack with a jerk, and frequently breaking the rope or the car coupling.

If the power fails while lowering a load, the disc 9 is traveling in a clockwise direction. When the power fails or is cut off, the core 33 of the solenoid 34 is permitted to move downwardly, thus moving the connecting rod 32 and the arm 29 downwardly, causing the cam 27 to move the forked weight arm upwardly. As the forked arm 19 is moved upwardly, the flattened surface 21 of the pin 20 strikes the pawl 22 and forces the end 25 of the pawl upwardly into engagement with the teeth 26 of the disc 9. When the pawl 22 engages with the disc 9 which is rotating in a clockwise direction, the force upon the pawl will rotate the latch arm about the bolt 13 and force the latch 15 free from the lever 43, thus causing the brakes to be applied in the usual way to stop the hoisting drum.

If the power fails during hoisting, or if it is cut off by an automatic safety controller because of improper retardation, the disc traveling in a counter-clockwise direction will not move the latch arm 14 until the hoisting drum comes to rest and under the influence of the load reversing starts back in the opposite direction. During the movement of the disc 9 in a counter-clockwise direction, the pawl which has been moved into engagement with the disc, as heretofore described when the power was cut off, rides upon the teeth 26 until the disc stops its movement in a counter-clockwise direction and starts moving in a clockwise direction. At this point, the latch arm is forced outwardly, thus releasing the lever 43 and causing the brakes to be applied in the usual way to stop the hoisting drum. Therefore, since the drum will not start in the reverse direction, except when the load is pulling it, the slack will be taken up when the brakes are applied in this case and the abnormal strain on the rope is eliminated.

In Figure 4, I have shown the hoist control, H. The brake drum shaft 44 is provided with a brake drum 45 concentric with which is disposed a brake band 46. The

cable drum 47 is also rigidly mounted upon the shaft 44 and is adapted to be checked in its rotation and stopped by the operative engagement of the brake band with the brake drum. The ends of the brake band 46 are pivotally secured to a double arm 48 which is keyed to a stub shaft 49. An arm 50 is also keyed to the shaft 49 at one end thereof. The other end of the arm 50 is pivotally secured to one end of a connecting rod 51. The other end of the connecting rod 51 is pivotally secured to a lever 52 which is keyed to a shaft 53. A weight arm 54 having a weight 55 mounted upon its outer end is also keyed to the shaft 53. A latch 56 is pivotally secured at 57 to the weight 55 and is adapted to engage with a cutaway portion 58 in a shaft 59. The lever 43 is rigidly mounted upon the shaft 59. A spring 60 is secured at one end to the frame of the hoist control and at the other end to the lever 43.

When the latch 15 is swung free from the lever 43, as heretofore described, the lever 43 is swung downwardly by the weight 55 until the latch 56 is freed from the shaft 59 and the lever 43 is returned to its uppermost position by the aid of the spring 60. However the weight 55 continues in its downward movement about the shaft 53 actuating the lever 52, the connecting rod 51, the arms 50 and 48, thus drawing the brake band into close engagement with the brake drum and stopping the rotation of the brake drum 45, the drum shaft 44, and the cable drum 47.

I claim:

1. The combination with a hoist having a cable drum, a brake mechanism for stopping the rotation of said drum, a lever for actuating said brake mechanism when released, and a hoist control, of means for holding said lever in set position, and means including a ratchet wheel and pawl cooperating with said hoist control for automatically releasing said brake lever when said hoisting drum is rotating in one direction, said means not releasing said brake lever when the hoisting drum is rotating in the opposite direction.

2. The combination with a hoist having a cable drum, a brake mechanism for stopping the rotation of said drum, a lever for actuating said brake mechanism when released, and a hoist control having a shaft, of means for holding said lever in set position, and means including a ratchet wheel and pawl cooperating with said shaft for automatically releasing said brake lever when said hoisting drum is rotating in one direction.

3. The combination with a hoist having a cable drum, a brake mechanism for stopping the rotation of said drum, a lever for actuating said brake mechanism when released, a hoist control having a shaft, of a toothed disc removably secured to said shaft, a latch arm for holding said lever in set position, and means cooperating with said toothed disc

for automatically releasing said brake lever.

4. The combination with a hoist control having a shaft operatively connected to a cable drum, a brake mechanism for stopping the rotation of said drum, a lever for actuating said brake mechanism when released, of an arm for holding said brake lever in the set position, a pawl pivotally mounted upon said arm, means for moving said pawl into operative position, and means removably mounted upon said shaft for engaging with said pawl for moving said arm for releasing said brake lever.

5. The combination with a hoist control having a shaft adapted to rotate in a clockwise and a counter-clockwise direction, of a toothed disc removably secured to said shaft, a latch arm, spring means for holding said arm in normal position, a pawl pivotally carried by said latch arm, and means for moving said pawl into engagement with said toothed disc when said disc is rotating in a counter-clockwise direction, said disc being adapted when rotated in a clockwise direction to engage with said pawl and move said latch arm out of normal position.

6. In a device of the type described, a toothed disc, a pawl, a weight arm, said weight arm adapted to engage with said pawl, a cam disposed in engagement with said weight arm, and means for moving said cam for raising said weight arm into engagement with said pawl and for raising said pawl into engagement with said toothed disc.

35 7. A device of the type described comprising a toothed disc, a latch arm, spring means for holding said latch arm in normal posi-

tion, a pawl rotatably mounted upon said latch arm, a weight arm adapted to engage with said pawl, a cam disposed in engagement with said weight arm, and means for actuating said cam for raising said weight arm into engagement with said pawl and for moving said pawl into engagement with said toothed disc, said toothed disc being adapted to rotate in a counter-clockwise direction, said disc being adapted when rotating in a clockwise direction to engage with said pawl and move said latch arm out of normal position.

8. A device of the type described comprising a rotatable toothed disc, a latch arm, yieldable means for holding said latch arm in normal position, a lever adapted to be held against movement by said latch arm when in normal position, means operatively connected to said lever for actuating a brake for stopping rotation of a cable drum when released by said lever, a pawl rotatably mounted upon said latch arm, a weight arm adapted to engage with said pawl, a cam disposed in engagement with said weight arm, and means for actuating said cam for raising said weight arm into engagement with said pawl and for moving said pawl into engagement with said toothed disc, said disc being adapted when rotated in one direction to engage with said pawl and move said latch arm out of normal position for releasing said lever, whereby said brake-actuating means will actuate said brake for stopping the rotation of said cable drum.

HENRY H. LOGAN.
